(57) **CLAIM**

The ornamental design for a baby carrier, as shown and described.

DESCRIPTION

FIG. 1 is a left side elevational view showing my new design for a baby carrier, shown in the closed condition;

FIG. 2 is a front elevational view thereof;

FIG. 3 is a front view, with the top flap of the head rest shown in the rolled condition;

FIG. 4 is a rear elevational view, shown with the head rest shown in the original condition;

FIG. 5 is a bottom plan view, shown in the opened condition;

FIG. 6 is a top, front perspective view, shown in the closed condition.

The heavy line weight broken lines shown in the drawings are for illustrative purposes only and form no part of the claimed design.

The light line weight broken lines shown in the drawings represent a stitching line.
